CLAIM

The ornamental design for a seismic sway brace fitting, as shown and described.

DESCRIPTION

FIG. 1 is a perspective view of a seismic sway brace fitting showing my new design;

FIG. 2 is a front elevational view thereof;

FIG. 3 is a right elevational view thereof;

FIG. 4 is a top plan view thereof;

FIG. 5 is a rear elevational view thereof;

FIG. 6 is a left elevational view thereof; and,

FIG. 7 is a bottom plan view thereof.

The broken lines in the drawings illustrate portions of the seismic sway brace fitting, which form no part of the claimed design.
